Walter Bryant of Boston Mass.
Letters Patent No. 314. Dated Sept. 24. 1850.

The Schedule referred to in these Letters Patent and making part of the same.

To all Persons to whom these Presents shall come:

Be it known, That I, Walter Bryant, of Boston, in the County of Suffolk and State of Massachusetts, have invented, or produced a new and useful design for an iron blower stand; and I do hereby declare that the said new design is fully described, and represented in the following Specification and accompanying drawings to which reference is hereinafter made.

The figures of the accompanying plate of drawings represent my new design. Fig. 1. is a front elevation of the blower stand, and fig. 2. is a transverse vertical section of the same.

My new design consists in forming the stand in two parts, a-a - a-a, each formed in contour in the shape of an ancient lyre frame, ornamented, as shown in fig. 1; the two upper ends terminating in the volute scroll, b-b, and each limb of the lyre frame terminating also in a volute scroll, c-c, which two scrolls come together in the reverse positions, and form the bottom of the lyre frame, as shown in the figure.

There is also a volute scroll, d-d, springing outwards from the center of each limb of the frame, and a curling leaf, e-e, turning inwards from the bottom of each limb, so as to touch each of the bottom scrolls, c-c. The two parts are precisely similar, and are put together by rivets, and supported on the ornamental standard, f-f.

Having thus described my new design for a blower stand, I shall state my claim as follows. What I claim as my invention or production, and desire to have secured to me by Letters Patent is, the new design hereinabove described for a blower stand, consisting in forming the two halves of said stand in the form of an ancient lyre frame, ornamented with volute scrolls, as hereinabove set forth, and as represented in the drawings.
